John Polhamus, of New York, N.Y.

DES. 2061

Letter Patent No. 2061-Dated May 9, 1865.

Design for a Spoon and Fork Handle.

The schedule referred to in these Letters Patents and making part of the case,

shall whom it may concern:

Be it known that, John Polhamus, of the City and State of New York, have originated and produced a new Design for the Handle of Forks, Spoons &c. and do hereby declare the following to be a correct description thereof, reference being had to the annexed drawing making part of this specification herein:

Figure 1 represents the design upon the upper or front side of the handle, and

Fig. 2 represents the design for the back of the handle.

The general shape of the outline of the handle is that of a shield at the end tapering to the narrow central portion of the handle.

At the edges of the handle, there are ribbon heads turned as shown.

At the junction of the handle with the fork or spoon, there are scrolls formed in relief as at A, and scroll work in relief is also formed at B, near the enlargement or bulb point of the handle.

At the end of the handle, there is formed a scroll and leaf design in relief, and the back of the handle near the same point has an ornamental ribbon head and scroll worked as ornaments as at C.

That claim and direct issue by Letters Patent is the design of the ornamental ribbon heads scroll and leaves for the front and for the back of the handle of a fork, spoon or similar article, as represented.

2   In witness whereof I have hereunto set my signature
